MANUALLY OPERATED KEY ATTACHING MEANS

**Alfred L. Kronquest, Syracuse, N. Y., assignor to
Continental Can Company, Inc., New York,
N. Y., a corporation of New York**

Application March 2, 1933, Serial No. 659,422

4 Claims. (Cl. 113—1)

4 Claims. (Cl. 113—1)

The invention relates to new and useful improvements in a machine for attaching keys to containers, which keys are to be separated from the container and used for opening the same.

5. An object of the invention is to provide a manually operated device which may be used for bending a portion of a key about the double seam or some other part of a container for securing the same thereto.

10 A further object of the invention is to provide a machine of the above type which may be quickly adjusted for operation upon containers of different heights.

In the drawings—

15 Figure 1 is a plan view of a machine embodying the improvements;

Fig. 2 is a side view of the same;

Fig. 3 is a vertical sectional view through the clinching head of the clinching machine with the clinching jaws separated, and

Fig. 4 is a similar view, but showing the clinching jaws closed upon the key for bending it about the double seam.

Figure 5 is a plan view of the key as made up for attachment to the container.

In my co-pending application Serial No.

659,423, filed of even date herewith, there is shown and described a machine for attaching keys to containers in which a clinching head traveling with the container engages the key and bends the same about the double seam of the container. The present invention has to do with a machine wherein the clinching head is manually operated, the broad invention being shown and claimed in my co-pending application.

The machine includes a supporting base 1 having a gauge member 2 secured thereto by a bolt 3 which may be utilized for positioning the container on the base. The container is indicated 40 in broken lines in Fig. 2 at 4. The container has the end 5 secured thereto by a double seam 6, which is of the usual construction. The container is provided with a tearing strip indicated in broken lines at 7 in Fig. 2, on the tongue of which 45 the key is placed, and then the strip is rolled onto the key for opening the container. The key is indicated at 8 in the drawings. Said key has a handle portion 9, and the body portion is slotted at 10 for the purpose just stated. Extending 50 beyond the slotted portion, the end of the key is flattened and formed into an open hook 11. This hook end 11 is placed over the double seam as shown in Fig. 3, and is then bent at the extreme outer end thereof under the double seam as indicated in Fig. 4. The purpose of the present ma-

(Cl. 113—1) A clinching device for assembling a double seam, the machine is to accomplish this bending of the key to attach it to the double seam. Mounted on the base 1 is a post or standard 12 which is secured in a sleeve 13 formed integral with the base by means of a clamping bolt 14. This standard 12 is of substantially uniform diameter. Attached thereto is a supporting bracket 15. Said supporting bracket 15 is provided with a split sleeve 16 which engages the standard 12, and a clamping bolt 17 draws the split sleeve together so as to clamp the standard, and thus hold the supporting bracket in a set position on the standard. In order to prevent the supporting bracket from rotating on the standard, it is provided with a key 15^a adapted to engage a slot extending lengthwise of the standard. The supporting bracket is provided with a cylindrical bearing member 18 in which is mounted a clinching head. The clinching head includes a sleeve member 19. Located in this sleeve member 19 is a supporting member 20 for the clinching devices. The supporting member has rigidly fixed thereto an inner clinching member or anvil 21. This anvil member is provided with a vertical shoulder 22. The lower face of the anvil adjacent the shoulder is curved upward slightly as indicated at 23. The lower end of the support 20 is provided with a slot 24. Located in this slot is a movable clinching finger 25. Said finger is carried by a pivot rod 26 which is mounted in the supporting bracket. A spring 27 tends to turn the clinching finger in a counter-clockwise direction as seen in Figures 3 and 4 and holds the same in engagement with an abutment 28 formed as a part of the sleeve 19. The clinching finger is provided with a downwardly project-

ing portion, the lower face 29 of which is substantially horizontal when the finger is in raised position. The inner face 30 extends substantially at right angles to the face 29. The supporting member 20 is provided with a stem 31 which extends up through the upper end of the sleeve 19. The sleeve has a recess 32 therein which is of slightly larger diameter than the stem 31. This recess terminates short of the top of the sleeve. A spring 33 located in the recess bears against the upper end of the sleeve as an abutment, and at its lower end against a shoulder on the supporting member. Mounted on the upper end of the stem 31 is an abutment plate 34. This abutment plate has a threaded connection with the upper end of the abutment stem 31, and is held in adjusted position by a set screw 35.

The sleeve is provided with a rack 36 in the inner side face thereof, which meshes with a segment gear 37 mounted on a shaft 38. The shaft 55

38 is journaled in the supporting bracket and is provided with a handle 39 whereby it may be turned manually in either direction. There is a dog 40 mounted in the recess in the supporting bracket with a spring beneath the same which constantly urges the dog into engagement with the segment gear. This dog is adapted to engage a recess 42 in the segment gear when the sleeve is in its extreme raised position, as shown in Fig. 2. When the operator through the handle 39 turns the segment gear, it will unseat the dog and the clinching head will be moved downward.

In Fig. 1 of the drawings, the head with the clinching devices is in its raised position. The container is placed against the gauge on the support with the key resting on the container with the hook end of the key in engagement with the double seam. The operator by turning the handle 39 moves the head downward until the abutment plate 34 contacts with the upper end of the bearing of the supporting bracket. During this movement, the support 20 and sleeve move together as a unit, and the inner clinching device or anvil 21 is brought down into engagement with the key, resting with sufficient firmness thereon so as to hold the key placed. At this time, the vertical wall 22 is directly in contact with the inner face of the hook end. A continued movement of the handle will lower the sleeve but not the support 20, as the abutment plate 34 is in contact with the supporting bracket, as noted. As the sleeve continues its downward movement, the abutment 28 will cause the clinching finger 25 to swing about its pivotal support and contact with the hook end of the key. The inner face of the clinching finger is so dimensioned that it will bend the hook end underneath the double seam and slide along the hook end producing the bend by the camming action of the inner face of this clinching finger. During this bending of the key end there is little or no strain placed on the container by reason of the fact that the abutment 34 limits the downward movement of the anvil 21. This abutment 34 may be adjusted and the pressure on the key regulated so that it is just sufficient to hold the key in place on the double seam during the clinching of the key to the double seam. The pressure of the clinching finger against the key end is taken by the anvil 21 at the inner portion of the key end, and this enables the key to be firmly crimped or clinched about the double seam. The key will remain connected to the container, and will not be dislodged through any handling or storing of the containers. It may, however, be quickly released by grasping the handle end of the key and lifting the same, which will bend the end of the key so as to release its connection from the double seam.

After having clinched the key to the container, the operator turns the handle in the opposite direction and raises the clinching head, and as soon as the sleeve starts on its upward movement, the clinching finger will be released and the spring 27 will move the same away from the key end. When the sleeve contacts with the abutment 34, it will lift the support 20 carrying the clinching fingers and raise them from the container to the position shown in Fig. 2. The container can then be quickly removed and another inserted for the next clinching operation.

It is obvious that minor changes in the details of construction and arrangement of the parts may be made without departing from the spirit of the invention as set forth in the appended claims.

Having thus described the invention, what I claim as new and desire to secure by Letters Patent, is—

1. A machine for clinching keys to containers comprising a support for the container, a standard carried thereby, a supporting bracket carried by the standard, a clinching head mounted on the supporting bracket for vertical movement, manual means for raising and lowering the clinching head, yielding means for holding the clinching head in raised position, said clinching head including a supporting member movable with the head and having a limited vertical movement therein, a spring for yieldingly holding said supporting member at the lower end of its movement, clinching devices carried by said supporting member, and means carried by said head for actuating the clinching devices when the head is moved downward relative to said supporting member. 5

2. A machine for clinching keys to containers comprising a support for the container, a standard carried thereby, a supporting bracket carried by the standard, a clinching head mounted on the supporting bracket for vertical movement, 10 manual means for raising and lowering the clinching head, yielding means for holding the clinching head in raised position, said clinching head including a supporting member movable with the head and having a limited vertical movement therein, a spring for yieldingly holding said supporting member at the lower end of its movement, a clinching anvil fixed to said supporting member, a clinching finger pivoted to said supporting member, an abutment carried by the clinching head and adapted to engage said clinching finger for moving the same toward the anvil when said head is moved relative to the supporting member, and a spring for normally holding said clinching finger in contact with said abutment. 15

3. A machine for clinching keys to containers comprising a support for the container, a standard carried thereby, a supporting bracket carried by the standard, a clinching head mounted on the supporting bracket for vertical movement, manual means for raising and lowering the clinching head, yielding means for holding the clinching head in raised position, said clinching head including a supporting member movable with the head and having a limited vertical movement therein, a spring for yieldingly holding said supporting member at the lower end of its movement, clinching devices carried by said supporting member, and means carried by said head for actuating the clinching devices when the head is moved downward relative to said supporting member, said supporting member having a stem projecting upwardly and carrying an adjustable abutment plate adapted to engage said bracket for limiting the downward movement of the supporting member. 45

4. A machine for clinching keys to containers comprising a support for the container, a standard carried thereby, a supporting bracket carried by the standard, a clinching head mounted on the supporting bracket for vertical movement, manual means for raising and lowering the clinching head, yielding means for holding the clinching head in raised position, said clinching head including a supporting member movable with the head and having a limited vertical movement therein, a spring for yieldingly holding said supporting member at the lower end of its 50

movement, a clinching anvil fixed to said supporting member, a clinching finger pivoted to said supporting member, an abutment carried by the clinching head and adapted to engage said clinching finger for moving the same toward the anvil when said head is moved relative to the supporting member, a spring for normally hold- ing said clinching finger in contact with said abutment, said supporting member having a stem projecting above the bracket, and an adjustable abutment plate carried thereby for engaging the bracket and limiting the downward movement of the supporting member. 5
